UNITED STATES PATENT OFFICE.

CHARLES S. ALDEN, OF ROCHESTER, NEW YORK.

POCKET-BOX FOR CIGARETTES, &c.

SPECIFICATION forming part of Letters Patent No. 376,056, dated January 10, 1888.

Application filed April 6, 1887. Serial No. 233,933. (Model.)

To all whom it may concern:

Be it known that I, CHARLES S. ALDEN, of Rochester, in the county of Monroe and State of New York, have invented a certain new and 5 useful Improvement in Pocket-Boxes for Cigarettes and Cigars; and I do hereby declare that the following is a full, clear, and exact description of the same, reference being had to the drawings accompanying this application.

My improvement relates to pocket-boxes for cigarettes and cigars; and the invention consists in the construction and arrangement hereinafter described and claimed.

15 In the drawings, Figure 1 is a plan view showing the box extended or laid open flatwise, one half being filled with cigarettes, the other half being empty. Fig. 2 is an enlarged cross-section of the box in the closed position, 20 the line of section being indicated by line xx of Fig. 1. Figs. 3 and 4 are enlarged longitudinal sections in lines yy and zz of Fig. 1.

A A' indicate the two parts of the box, each forming a counterpart and hinged at a , so that 25 either part can be thrown up as a cover to open the box, as in Fig. 1. One part of the box is provided with a spring-catch, b , which catches the other part when closed and holds the two parts together. The box is made of 30 thin and light sheet-brass or other suitable material.

The bottom or flat portion of each half of the box is struck up or formed with corrugations $c c$, of such size as to receive the cigarettes $d d$. The cigarettes fill the corrugations and lie close together. By thus corrugating the box the cigarettes are got into less space, and are held more compactly and securely, and the box is made much stronger and stiffer, 40 and it presents a better appearance. The corrugations do not extend quite to the ends of the box; but blanks $e e$ are left outside, standing at the same level as the bottom of the corrugations, and said ends are left of the usual 45 square or rectangular form, which adds to the good appearance of the box.

D D' are two swinging arms, forming binders. They consist of spring-strips jointed around the hinge a , so as to turn freely, and 50 provided at the opposite or outer end with right-angled nibs ff , that form catches or hold-

ers. These arms extend across the box, and when closed down in place the nibs ff spring down inside the outer edge of the box, and thus hold the arms in place by the spring 55 pressure and contact. They swing in opposite directions and cover both halves of the box. If desired, the arms may be hinged at the outer edges of the box and turn inward, instead of being hinged at the center and turning outward. If desired, also, two or more of the binders may be used with each half of the box.

To pack the cigarettes in place, the binders are thrown open, which leaves the whole space 65 clear. When the cigarettes are packed, the binders are turned over them and secured, which holds the cigarettes firmly in place and prevents them from dropping out. The binders are preferably located a little distance in 70 from the ends of the box, as shown, so that the cigarettes can be drawn out endwise without raising the binders. For cigars the box is simply made larger, the same construction being involved.

75 Another use of the binders is to furnish space for advertisements, which are printed or stamped on the flat surfaces of the binders. It is designed to furnish these boxes so cheaply that dealers can afford to give them away to 80 their customers with each purchase of a certain quantity of goods.

Each half of the box is struck up and the corrugations formed at one and the same operation by the use of suitable dies.

Having described my invention, what I 85 claim as new, and desire to secure by Letters Patent, is—

The combination, with the box consisting of halves provided with corrugations in the bottoms and blanks at the ends of the corrugations, of binders hinged at one end to the box and shutting over the halves of the box, in the manner and for the purpose specified.

In witness whereof I have hereunto signed 95 my name in the presence of two subscribing witnesses.

C. S. ALDEN.
